UNITED STATES PATENT OFFICE

2,486,878

REVERSIBLE SHELL FEEDER

Francis I. Rataiczak, Dayton, Ohio, assignor to
 General Motors Corporation, Dayton, Ohio, a
 corporation of Delaware

Application January 1, 1945, Serial No. 570,906

12 Claims. (Cl. 89—33)

1

This invention relates to ordnance and more particularly to an improved machine gun construction.

This application is a continuation in part, of my copending application S. N. 536,229, filed May 19, 1944.

One object of this invention is to provide an improved shell feeding mechanism.

More specifically, it is an object of this invention to provide an improved shell feeding mechanism which may be changed over from a righthand feed to a lefthand feed very quickly.

A further object of this invention is to provide an improved shell feeding mechanism which prevents jamming of the gun due to improper feeding.

A still further object of this invention is to provide means for preventing overfeeding.

Another object of this invention is to provide a cartridge hold-down mechanism which permits a cartridge which has prematurely moved into place above the feed opening in the feedway to move upwardly out of the way of the bolt mechanism upon recoil so as to prevent jamming the gun.

Still another object of this invention is to provide an improved shell feeding mechanism which is interchangeable with the corresponding mechanism of other guns.

Further objects and advantages of the present invention will be apparent from the following description, reference being had to the accompanying drawings, wherein a preferred form of the present invention is clearly shown.

In the drawings:

Fig. 1 is a side elevational view of a gun embodying my invention;

Fig. 2 is a horizontal sectional view looking down on parts of the shell feeding mechanism when removed from the breech cover and is taken on line 2—2 of Fig. 3;

Fig. 3 is a vertical sectional view taken on line 3—3 of Fig. 4 and shows the relationship of the shell feeding mechanism to the cover and the cam tube;

Fig. 4 is a sectional view taken on line 4—4 of Fig. 2;

Fig. 5 is an elevational view, partly in section, showing the shell or belt feed slide assembly;

Fig. 6 is an elevational view of the one type of cartridge depressor;

Fig. 7 is a sectional view taken on line 7—7 of Fig. 5;

Fig. 8 is a fragmentary sectional view taken on line 8—8 of Fig. 3 illustrating the manner in

2

which the belt feed slide assembly is locked in place relative to the cover;

Fig. 9 is a fragmentary sectional view similar to Fig. 4 but showing a modified shell feeding construction;

Fig. 10 is a sectional view taken substantially on line 10—10 of Fig. 9;

Fig. 11 is an elevational view showing the feed pawl arm;

Fig. 12 is a sectional view taken substantially on line 12—12 of Fig. 9;

Fig. 13 is a sectional view taken substantially on line 13—13 of Fig. 10;

Fig. 14 is a perspective view of the mechanism shown in Figs. 10 through 13 showing the bottom of the shell feeding mechanism with the shell feeding rack removed;

Fig. 15 is a perspective view looking downwardly upon a gun with the cover raised showing the arrangement of the modified shell feeding mechanism for lefthand feed; and

Fig. 16 is a view similar to Fig. 15 but showing the arrangement of the shell feeding mechanism for righthand feed.

25 Referring now to Fig. 1 of the drawing, reference numerals 50, 52 and 54 designate the receiver housing, the barrel, and the cover respectively, of a .60 caliber rapid fire machine gun embodying my invention. The cover for the receiver housing is pivotally secured to the receiver housing at 56. A belt feed mechanism, generally designated by the reference numeral 58, is removably secured to the cover member 54 whereby the mechanism 58 may be removed and turned end for end so as to change over from righthand feed to lefthand feed or vice versa in a manner to be explained more fully hereinafter. A feedway 60 is carried by the receiver housing 50 and cooperates with the belt feed mechanism to direct the feed belt and the cartridges carried thereby into the breech housing 50. A cartridge stop assembly 62 is removably secured to the feedway 60 and serves to stop the cartridges over the slot 285 in the feedway and prevents the cartridges from moving all the way across the feedway.

30 There are two shell feeding mechanisms disclosed herein, the first of which is shown in Figs. 2 through 8 and corresponds to the shell feeding mechanism disclosed in my above mentioned copending application. Since this application is directed primarily to the construction and operation of the shell feeding mechanism, the details of the remaining gun parts will not be described herein except insofar as necessary for an understanding of the operation of the shell feed-

ing mechanism covered in this application. For a more complete description of the other parts of the gun, reference is hereby made to the specification and drawings in said co-pending application.

For certain types of gun installations it is desirable to feed the shells into the gun from the right hand side of the gun whereas in other gun installations it is desirable to feed the shells into the gun from the left hand side of the gun. It is also desirable to make all guns alike insofar as possible and to arrange the parts so that the shells may be fed into any gun from either side merely by making a few simple changes. In the construction used in this gun, the change over from lefthand feeding to righthand feeding may be made very simply and quickly.

As explained in my co-pending application, the belt or shell feeding mechanism is operated by the cam tube 206 which operates the belt feed slide assembly 216. The shells are carried by a suitable belt which comprises a plurality of cartridge engaging links in accordance with well-known practice. The belt feed slide assembly 216 is slidably supported on the feed rack support element 250 which in turn is carried by the housing element 252 as best shown in Fig. 4. The housing 252 projects from opposite sides of the cover 54 as shown in Fig. 3. A pair of belt feeding pawls 254 are pivotally carried by the belt feed slide assembly 216 and are adapted to engage the links of the belt. Dot dash lines have been used in Fig. 4 to show a conventional cartridge and belt link. A compression spring 256 biases the belt feeding pawls 254 downwardly into belt engaging position. The arrangement of the belt feed slide assembly is such that rotation of the tube 206 causes the pawls 254 to feed the shells into the breech housing from whence the shells are moved into the chamber of the gun barrel by the bolt head 156 as the bolt head moves forward.

A pair of belt holding pawls 260 are mounted on stationary pivots 262 and normally serve to prevent the shells from moving away from the breech housing when the belt feed pawls 254 move away from the breech housing to pick up a new shell. The belt holding pawls 260 are each biased into belt holding position by a compression spring such as the spring 264. By virtue of the above described arrangement the pawls 260 will allow the cartridges carried by the belt to move in the one direction only and will prevent movement in the wrong direction.

A pair of slideable cartridge depressors 272 are provided, each of which has a cartridge depressing pawl or projection 274. Each of the cartridge depressors is slidably mounted within the housing 252 and is biased into the full-line position shown in Fig. 3 by a compression spring 276. Each of the compression springs 276 is mounted on a pin 278. Each of the pins 278 is rigidly secured to a lug 280 which is punched out of the side wall of the feed rack support 250 as best shown in Fig. 2. The free end of each pin operates within a slot 281 formed in the turned end of the corresponding cartridge depressor as shown in Fig. 2.

Referring now to Fig. 3 in which I have shown the various positions of the cartridges as they move into the breech housing, it is apparent that the lug 274 projects downwardly too far to allow the cartridge to pass thereunder while sliding on the feedway 60. As a consequence thereof the cartridge depressor is forced to move ahead of

the cartridge until the cartridge is properly lined up with the slot 285 provided in the feedway 60 and the bolt head 156 has moved away from beneath the slot at which time the cartridge drops down and the lug 274 moves back over the cartridge so as to hold it in place until the bolt head shoves the cartridge ahead into the chamber of the gun barrel. The guide plate 286 carried by the cover 54 helps to guide the cartridge into place.

The plate 286 may be removably secured to the cover in any suitable manner and is provided with a flange 288 which holds the flange 290 of the housing 252 in place (Fig. 8) so as to make it impossible to remove the housing 252 without first removing the guide plate 286.

The housing 252 is also held in place relative to the cover 54 by means of a pair of latch elements 292 as best shown in Fig. 8. The latch elements 292 are carried by the studs 294 which are slidably supported in the side walls of the element 250. Normally the latch elements 292 and the studs 294 are held in latching position by the belt feed slide assembly 216. The outer ends of the latch elements 292 interlock with the slots 296 provided in the plates 298 and the adjacent side wall of the cover 54 as shown. As best shown in Fig. 3 reinforcing plates 298 are secured to the side walls of the cover 54 so as to reinforce the cover at this point. By virtue of the above described arrangement it is necessary to remove the belt feed slide assembly 216 from the housing 252 before it is possible to disengage the latches 292.

As best shown in Fig. 4 the lower ends of the element 250 are inturned so as to form the lower guides for the belt feed slide assembly 216. Strips 300 are attached to the inner sides of the element 250 so as to provide the upper guides for the belt feed slide assembly 216.

In order to remove the belt feed slide assembly from the housing 252 it is necessary to remove the mechanism within the cam tube 206. This mechanism may be removed by lifting the cover 54 and sliding out the mechanism from within the cam tube 206, as explained in my co-pending application. This mechanism being removed, the cam tube is free to rotate whereby the slide assembly 216 may be removed from the housing 252 through the end slot 253 (Fig. 1). Removal of the slide assembly 216 makes it possible to disengage the latch elements 292 from the slots 296 (see Fig. 8) whereby the housing 252 may be removed.

The slot 210 provided in the cam tube may be arranged for feeding the shells into the receiver from the righthand side (see Fig. 16) or it may be arranged to feed the shells into the receiver from the lefthand side (see Fig. 15). When it is desired to change over from righthand shell feeding to lefthand shell feeding it is necessary to change the cam tube so as to change over from a cam tube having a righthand helical slot to a cam tube having a lefthand helical slot. It is also necessary to remove the housing 252 and reverse it end for end so as to move the belt feeding and holding pawls from the one side of the gun to the other side of the gun.

It will be noted that there are two cartridge depressors 272, whereas only one cartridge depressor is required for feeding in a given direction. The reason for providing two is to always have one close to the rear end of the cartridge for holding the cartridge down regard-

less of which way the housing 252 is arranged.

In order to make it possible to clear the gun of any cartridges and so as to disengage the shell feeding belt from the pawls 254 and 260 I have provided a shaft 330 which is pivoted in the side walls of the housing 252 and which is provided with a pair of handles 332 disposed on the outside of the casing 252. The shaft 330 has secured thereto five cam levers 334, 336, 338, 340 and 342 which function in the following manner upon rotating the shaft from the position in which it is shown in Figs. 3 and 4 in a counter clockwise direction as viewed in Fig. 3. The cams 336 and 340 engage the belt holding pawls 260 adjacent the upper ends thereof so as to lift the lower ends of the pawls 260 out of the path of the links of the belt and the cartridges carried by the links. The pawls 334 and 342 engage the cartridge depressor cranks 344 which serve to engage the cartridge depressor slide elements 272 so as to move them out of cartridge depressing position. The cam lever 338 has its free end pivotally secured to a spring abutment element 348 which is also pivotally secured to an arm 350 carried by the shaft 352 which also carries the cartridge depressor cranks 344. The element 348 moves downwardly as the free ends of the levers 338 and 350 move downwardly in response to operation of the handles 332. This downward movement of the element 348 causes the element 348 to engage the upper end of the pawls 254 so as to lift these pawls at the same time that the pawls 260 are lifted. The arm 350 and the cranks 344 are free to rotate on the shaft 352. A spring 354 biases the element 348 into the position in which it is shown in Figs. 2 and 3 and serves to hold the cam segments 334 to 342 in the position in which they are shown in Figs. 2 and 3.

For purposes of illustration, the cartridge depressors 272 have been shown as slidable elements biased into cartridge depressing position by springs 276 whereas the cartridge depressors could be pivoted levers biased into cartridge depressing position by suitable spring means which would yieldably hold the cartridge depressed so that if a cartridge would begin to move into place before the bolt head has moved back, it would be possible for the cartridge to move up out of the path of the bolt head so as to allow the bolt head to move back. This latter type of cartridge depressor is used in the modification shown in Figs. 9 through 16.

In certain types of gun installations, the inertia effect of the cartridge belt tends to feed the cartridges into the gun more rapidly than desired. Various arrangements may be used to compensate for this inertia effect. One such arrangement, for example, which may be used, comprises a suitable friction means for resisting the movement of the belt so that the belt will not move faster than the feed pawl 254 directs. Another arrangement has been illustrated herein in Figs. 9 through 16.

A modified form of feed mechanism is shown in Figs. 9 through 16 which may be used in place of the mechanism shown in Figs. 2 through 8 without altering the cover and cam tube construction.

The construction and operation of many of the parts in the modification shown in Figs. 9 through 16 are identical or very similar to the construction and operation of the corresponding parts shown in Figs. 2 through 8 of the drawing. The same reference numerals are used to

designate parts of the two feed mechanisms which are identical or similar in construction and operation.

One manner in which the mechanism of Figs. 9 through 16 differs from the mechanism described hereinabove and shown in Figs. 2 through 8, is in the construction of the means for holding the cartridges down after they move in line with the feed slot 285 in the feedway 60. Thus, in place of providing two permanent slidable cartridge depressors such as the depressors 272, I have provided two interchangeable cartridge hold-down levers 400 (see Figs. 9, 10, 13 and 14). One of the levers is used when cartridges are to be fed in from the left and the other is used when cartridges are to be fed in from the right. The two levers are alike except for minor details. Thus, the one is made to fit snugly against the one side wall of the casing 252 and the other is made to fit snugly against the opposite side wall. The particular hold-down lever used at any one time is journaled on the removable pin 402 which is arranged adjacent one end of the casing or housing 252. A coil spring 404 (see Fig. 10) pushes down on the hold-down lever so as to yieldably hold the cartridges down in place as the bolt head 156 pushes the cartridge forward into the bore of the gun. A slot 406 is provided in each hold-down lever 400 for limiting the travel of the hold-down lever. A removable stop rod 408 passes through the slot 406 as shown. In Fig. 15, I have shown a cartridge hold-down lever of the type used for lefthand feed whereas in Fig. 16 I have shown the type of cartridge hold-down lever used for righthand feed.

By virtue of the construction and arrangement of the cartridge hold-down levers 400, it is apparent that in the event that a cartridge prematurely moves into place above the slot 285 before the bolt head has had a chance to move back, the cartridge together with the cartridge hold-down lever may be elevated by the bolt head so as to allow the bolt head to pass under the cartridge without jamming the gun.

In the shell feeding mechanism disclosed in Figs. 2 through 8 no provision was made for lifting the belt feed pawls in the event of overfeed. Under certain circumstances, the inertia of the cartridges and the cartridge links is sufficient to prematurely feed a cartridge without the aid of the belt feed pawl and prior to the time that the belt feed pawl has moved into cartridge feeding position. In order to prevent jamming of the gun under such circumstances, I have provided an auxiliary arm 410 which has its lower end 412 arranged directly above the cartridge slot 285 provided in the feedway 60 as shown in Fig. 10. The auxiliary arm 410 is pivoted at 414 on a pin 416 as shown in Figs. 10 and 11. A compression spring 417 biases the end 412 into cartridge engaging positions (see Figs. 9, 12 and 13). The upper end of the arm 410 is provided with a slot 418 which is arranged in engagement with a pin 420 carried by one of the links 422. The links 422 are secured to the shaft 424 (see Fig. 13), which also has secured thereto a link 426 for operating the belt feed pawl depressor 430 which is arranged to pivot about the shaft 330. By virtue of the above described arrangement, if a cartridge prematurely moves into place beneath the lower end 412 of the arm 410, the lower end 412 will be elevated thereby causing the belt feed pawl depressor 430 to push down on the upper end of the belt feed pawl 254 so as to elevate the lower end of the belt feed pawl

as shown in Fig. 12 with the result that as the belt feed slide 70 moves the belt feed pawl 254 towards the center of the feedway 60, it will not try to force an extra cartridge into the center position.

In comparing the construction of the device shown in Fig. 2 with the construction of the device shown in Fig. 13, it will be noted that the spring 354 together with the spring abutment element 348 shown in Fig. 13, has been moved off to one side so as to make room for the belt feed pawl depressor 430.

As shown in Figs. 15 and 16, only one auxiliary arm is used at any one time but two separate auxiliary arms are provided which are very similar in construction but one of which is used for righthand shell feeding and the other of which is used for lefthand shell feeding. In other words, when it is desired to change over from lefthand feed to righthand feed, it is necessary to remove the righthand auxiliary arm and substitute for it a lefthand auxiliary arm on the opposite side of the housing element 252 from the right hand feed position. In either feed, the auxiliary arm is always nearest the cover pivot 56. The inner ends of the pins 416 which support the auxiliary arms are threaded into a tapped recess in the feed rack support 250 as best shown in Figs. 9 and 13. As shown in Figs. 10 and 13 there are two pins 416 provided. These pins also serve as the pivots for the belt holding pawls 260.

As in the construction shown in Figs. 2 through 8, the belt holding pawls may be lifted out of belt holding position by operating one or the other of the handles 332. At the same time that operation of the handles 332 lifts the belt holding pawls out of belt holding position, the spring abutment element 348 pushes down on the upper end of the belt feed pawls so as to raise the lower ends of the belt feed pawls. This operation is the same as that described in connection with the construction shown in Figs. 2 through 8.

While the form of embodiment of the invention as herein disclosed constitutes a preferred form, it is to be understood that other forms might be adopted, as may come within the scope of the claims which follow.

What is claimed is as follows:

1. A shell feeding mechanism for use in feeding shells into the receiver of a rapid fire machine gun comprising in combination, a receiver, a casing having portions projecting from opposite sides of said receiver, a belt feeding rack supported within said casing, a feed rack support carried by said casing for supporting said feed rack, a belt feeding pawl mounted on said feed rack, a pair of belt holding pawls mounted within said casing for preventing movement of the cartridge belt in the wrong direction, a pair of cartridge depressors carried by said casing, said casing and the belt feeding and holding pawls supported thereby being adapted to be turned end for end as a unit upon change over from righthand shell feeding to lefthand shell feeding.

2. In a rapid fire machine gun, a receiver housing, a cover for said receiver housing, shell feeding mechanism carried between said receiver housing and said cover, said shell feeding mechanism comprising a reversible casing carried by said cover and having pivoted spring biased belt feeding and holding pawls disposed in the casing upon one side of the receiver housing and having a pivoted spring biased cartridge hold-down

lever disposed in the casing on the other side of the receiver, means for removably mounting said casing in either of two positions relative to said cover whereby said casing is removable from said cover and reversible so as to change over from a righthand feed to a lefthand feed.

3. In a machine gun, a receiver, a casing, a feed rack support carried by said casing, a feed rack slideable in said support, shell feeding pawl means carried by said feed rack, means for removably securing said casing to said receiver, and means for preventing removal of said casing from said receiver when said feed rack is in a predetermined position.

15 4. In a rapid fire machine gun, a receiver housing, a covering for said receiver housing, shell feeding mechanism carried between said receiver housing and said cover, said shell feeding mechanism comprising a casing, means for removably securing said casing to said cover, belt feeding pawls and belt holding pawls disposed in the casing on one side of said receiver, said casing and said cover having interengaging parts whereby said casing and said belt feeding and holding pawls are removable from said cover and reversible end to end so as to change over from a right-hand feed to a left-hand feed.

5 5. In a machine gun, a receiver, a cover for said receiver, a shell feeding casing, a feed rack support carried by said casing, a feed rack slideable in said support, a belt feeding pawl carried by said feed rack, a pair of belt holding pawls, means including fixed pivots for pivotally mounting said pawls within said casing, cartridge depressor means, means for supporting said cartridge depressor means within said casing, and means for removably securing said casing to said cover whereby said casing may be reversed end for end for reversing the feed.

40 6. In a machine gun, a receiver provided with a cover, a reversible shell feed casing, a feed rack support carried by said casing, a feed rack slideable in said support, holding means for removably securing said casing to said cover including means carried by said casing for locking said casing in place relative to said cover, said last named means being held in locking position by said feed rack when said feed rack is in shell feeding position within said casing.

50 7. In a machine gun, a receiver, a casing having one portion adapted to project on one side of said receiver and having another portion adapted to project on the other side of said receiver, a feed rack support carried by said casing, a feed rack slideable in said support, a belt feeding pawl carried by said feed rack, a pair of belt holding pawls pivotally mounted within said casing, cartridge depressor means carried within said casing, and means for removably securing said casing to said receiver whereby said casing may be turned end for end so as to change over from right-hand shell feeding to left-hand shell feeding.

65 8. In a rapid fire machine gun, a receiver housing, a cover for said housing, shell feeding mechanism disposed within said housing, said shell feeding mechanism comprising a casing reversible end to end and disposed between said cover and said housing, said casing having flanges projecting from opposite sides thereof, a cartridge guide plate, means for securing said guide plate to said cover, said guide plate having a projecting flange portion adapted to overlap one of said flanges on said casing so as to hold said casing in assembled relationship relative to said cover.

70 9. In a rapid fire machine gun, a receiver hous-

ing, a cover for said housing, shell feeding mechanism comprising a casing reversible end to end and disposed between said cover and said housing, said casing having flanges projecting from opposite sides thereof, a cartridge guide plate, means for securing said guide plate to said cover, said guide plate having a projecting flange portion adapted to overlap one of said flanges on said casing so as to hold said casing in assembled relationship relative to said cover.

75 9. In a rapid fire machine gun, a receiver hous-

ing, a cover for said housing, shell feeding mechanism disposed between said cover and said housing, said shell feeding mechanism comprising shell feeding pawls and a casing which serves as a support for said shell feeding pawls, and means for removably supporting said casing between said cover and said housing, said last named means being so constructed and arranged as to allow reversing said casing end for end.

10. In a rapid fire machine gun; a receiver housing; shell feeding mechanism for feeding shells into said receiver housing; and means for reversibly supporting said shell feeding mechanism relative to said housing; said shell feeding mechanism comprising a casing having end portions adapted to project on opposite sides of said housing, belt feeding pawl means disposed within one of said projecting ends of said casing, and cartridge depressor means disposed within the other end of said casing whereby upon reversal of said casing said pawl means are transferred from one side of said receiver housing to the other side of said receiver housing.

11. In a rapid fire machine gun, a receiver housing, a cover for said housing, shell feeding mechanism adapted to be disposed between said cover and said housing for feeding shells into said housing comprising a reversible casing having end portions adapted to project on opposite sides of said housing, support means for removably supporting said casing between said cover and said housing whereby said casing is reversible end to end, shaft means permanently mounted within one end of said casing, shell engaging pawl means permanently mounted upon said shaft means whereby upon reversal of said casing said pawl

means are transferred from one side of said housing to the other side of said housing.

12. In a rapid fire machine gun, a receiver housing, a cover for said housing, shell feeding means disposed between said cover and said housing, said shell feeding means comprising a casing having end portions disposed on opposite sides of said cover and having its central portion cut away for the reception of said cover, said casing having the shell feeding mechanism disposed on one side of said housing, and supporting means for removably supporting said casing relative to said housing, said last named means being arranged to support said casing relative to said cover with the shell feeding mechanism disposed on either side of said housing.
